UNITED STATES PATENT OFFICE.

ROBERT HARDIE, OF ROME, NEW YORK, ASSIGNOR TO THE GENERAL COMPRESSED AIR COMPANY, OF NEW YORK, N. Y.

AIR-STORAGE MOTOR-CAR.

SPECIFICATION forming part of Letters Patent No. 616,922, dated January 3, 1899.

Application filed February 1, 1897. Renewed September 10, 1898. Serial No. 690,687. (No model.)

To all whom it may concern:

Be it known that I, ROBERT HARDIE, a citizen of the United States, residing at Rome, in the county of Oneida and State of New York, 5 have invented certain new and useful Improvements in Air-Storage Motor-Cars; and I do hereby declare the following to be a full, clear, and exact description of the invention, such as will enable others skilled in the art to 10 which it appertains to make and use the same.

My invention has for its object to provide a certain detail of improvement in the air-storage motor-car or locomotive which is fully disclosed in my pending application for 15 United States Letters Patent, filed September 2, 1896, under Serial No. 604,621, entitled "Air-storage motor-cars." In the said air-storage motor-car or locomotive, as will appear from said pending application, the air 20 is carried on the car at an initial pressure of about two thousand pounds in suitable reservoirs. From these high-storage-pressure reservoirs the air passes first through a suitable reduction-valve for reducing the same to 25 the desired working pressure of about one hundred and fifty pounds, and thence through a hot-water air-reheater and out through the throttle-valve and piping to the cylinders of the car-driving engines. The working-pres- 30 sure pipe at some point between the reduction-valve and the reheater is tapped by a supply-pipe leading to a combination-valve which controls the supply to a brake-motor and to supplemental starting connections for 35 the driving-engines. One or more check- valves are located in the working-pressure pipe between the reduction-valve and the reheater; and the said supply-pipe for the combination-valve taps the said working-pressure 40 pipe between the said check-valve adjacent to the reheater and the said reduction-valve. The object was to secure dry or unmoistened air for use in the brake-motor and for start- 45 ing the engines under the control of said combination-valve. The object of the check- valve adjacent to the reheater was to keep the water from backing up into the working- pressure pipe and the said connections tap- ping the same between said check-valve and 50 said reduction-valve. In practice, however, it was found that in some instances, in case

of an excessive draft to the combination-valve for the brake-motor or the starting connec- 55 tions, the pressure between the said check- valve and the reduction-valve would be tem- porarily reduced to such an extent that the air would flow back from the reheater and carry more or less water with the same into the said piping, controlled by said combina- 60 tion-valve. This was of course a serious ob- jection, and to overcome the same I have provided and applied a drip-pocket or water- trap in the working-pressure pipe between the check-valve at the reheater and the point at which the said supply-pipe to the combina- 65 tion-valve taps said working-pressure pipe. This drip-pocket is so arranged that whatever water may come back from the reheater when the combination-valve is in use—as, for ex- 70 ample, to set the brake or for starting the driv- 75 ing-engines—will be caught in the said trap or pocket. Then when the combination-valve is closed, so that the air takes its normal course from the reduction-valve into the re- 80 heater, this movement of the air will force back into the reheater whatever water may have been caught in the drip-pocket. By this detail of improvement I avoid the accumula- 85 tion of any water in the piping which is con- trolled by the combination-valves, thereby avoiding the injurious results which would 90 follow from water in the said pipes.

The invention is illustrated in the accom- 95 panying drawings, wherein like notations refer to like parts throughout the several views.

Figure 1 is a plan view of a part of the air- storage motor-car piping, such as was dis- 100 closed in my pending case, but shown as equipped with my present improvement. Fig. 2 is a view of the same, chiefly in right-end elevation, but partly in cross-section; and Fig. 3 is a detail showing the drip-pocket or trap detached.

Only so much of the piping and the work- 105 ing system of said air-storage motor-car has been illustrated as is deemed necessary to illustrate my present improvement.

The numeral 1 represents the pipe-sections which lead from the high-pressure-storage reservoirs (not shown) at the opposite ends of the car-truck frame to a fitting 2, and thence through pipe-sections 3 to the reduction-

valve 4. From the reduction-valve 4 the air passes at the reduced or working pressure through pipe-section 5 and check-valve 6 into pipe-section 7. The pipe-section 7 connects 5 to fitting 8, from which a curved pipe-section 9 leads to the drip-pocket or trap 10, tapping the same at its highest interior level. From the drip-pocket 10 a pipe-section 11 leads to the check-valve 12, and thence pipe- 10 sections 13, 14, and 15 lead into the hot-water air-reheater 16. The pipe-section 11 taps the drip-pocket 10 at the lowest level therein. From the hot-water air-reheater 16 the air passes out through pipe 17 to the throttle- 15 valve 18, which is under the control of the throttle-lever 19. Thence the air passes by pipe-sections 20 to the valve-chests of the driving-engines 21.

The fitting 8 is tapped by pipe-sections 22, 20 which lead to the combination-valves 23, only one of which is shown. From the combination-valves 23 pipe connections 25 and 26 extend to opposite ends of the brake-motor cylinder 27 for the operation of the brake-motors 25 to set or release the brakes at will under the control of the combination-valves 23. From the said combination-valves 23 also extend pipes 28 to a fitting 29, whence branches 30 extend to pipes 31, leading to suitable ports 30 (not shown) in the seats of the distribution-valves (not shown) for use in starting the engines when the riding cut-off valves are in their cut-off positions. Otherwise stated, the combination-valves 23 control the brake-motor 35 and the starting connections for the car-driving engines. It will be seen that the supply of air to said combination-valves 23 is effected through the pipe-sections 22 and is drawn from the working-pressure pipe at the 40 fitting 8 or a point in the working-pressure system between the check-valves 6 and 12; but the drip-pocket 10 is located between the check-valve 12 and the said fitting 8. Hence if the draft occasioned by the use of the combination-valve for setting the brake or for 45 starting should so reduce the pressure in the working-pressure pipe as to cause the air to flow back from the heater 16 and carry more or less water therewith through the check-valve 50 12 the same will pass through the pipe-section 11 into the drip-pocket 10 at the lowest level therein and be caught by the said pocket, while the air will pass on outward through the pipe-section 9 from the upper level of the 55 pocket or trap. Then when the combination-valve is thrown into its closed position or the air is otherwise permitted to take its normal course from the reduction-valve 4 into the reheater 16 the air-pressure through the pipe- 60 section 9 will force the water back from the pocket or trap 10 through the pipe-section 11, check 12, and connections 13, 14, and 15 into the reheater 16. As the backflowage or leakage through the check 12 is slight and can 65 only occur at the times when an excessive draft is produced on the working-pressure pipe between the checks 6 and 12 for afford-

ing the necessary supply to the combination-valve 23, this drip-pocket 10 is ample to catch and subsequently return any water that may 70 come into the same from the reheater. In this combination, therefore, the drip-pocket is entirely automatic in its action. Otherwise stated, it catches the water under the backflowage of air and water from the reheater 75 and again clears itself when the air takes its normal course from the reduction-valve into the reheater. This combination is therefore a valuable one in the practical working of the system, for the reason that dry air is 80 thereby insured in all the piping or connections controlled by the combination-valves 23. If water were permitted to accumulate in said piping or connections controlled by said combination-valves 23, the control of the car 85 might and probably would be seriously impaired. If by freezing or other cause the brake-motor or the starting connections could not be successfully operated, it is obvious that the control of the car would be in a large 90 measure lost.

From the foregoing it will be seen that with this system reheated and moistened air is normally used in the driving-engine, but that for certain other purposes, such as the 95 brake-motor and the starting connections, dry air is desired. Hence the pipe-sections 22 may be regarded as dry-air-supply pipes tapping the working-pressure system between the reheater and the reduction-valve to afford a supply of dry air for the brake-motor, starting connections, &c., and by the addition of the drip-pocket 10, applied and arranged as described, the desired dry air is absolutely insured without interfering with the 105 other desired actions of the system.

What I claim, and desire to secure by Letters Patent of the United States, is as follows:

1. In an air-storage motor-car or locomotive, the combination with a reduction-valve and a hot-water air-reheater through which the air is usually passed before entering the car-driving engine or engines, of a dry-air-supply pipe, for a brake-motor or other purpose, tapping the working-pressure pipe between said reheater and said reduction-valve, and a drip-pocket or water-trap, in said working-pressure pipe, between said reheater and said dry-air-supply pipe, substantially as and 110 for the purposes set forth.

2. In an air-storage motor-car or locomotive, the combination with a reduction-valve and a hot-water air-reheater through which the air is usually passed before entering the 115 car-driving engine or engines, of a water-check valve in the working-pressure pipe between said reduction-valve and said reheater, a dry-air-supply pipe, for a brake-motor or other purpose, tapping said working-pressure pipe between said water-check valve and said reduction-valve, and a drip-pocket or 120 water-trap in said working-pressure pipe between said water-check valve and said dry- 125

air-supply pipe, substantially as and for the purposes set forth.

3. In an air-storage motor-car or locomotive, the combination with a reduction-valve and a hot-water air-reheater, through which the air is usually passed before entering the driving engine or engines, of a water-check valve in the working-pressure pipe between the reduction-valve and the re heater, a dry-air-supply pipe, for a brake-motor or other purpose, tapping said working-pressure pipe between said water-check and said reduction valve, and the drip-pocket or water-trap in the working-pressure pipe, between said water-check and said reduction valve, with the dry-air connections 9 tapping the trap at its highest level and the water or wet-air connection 11 tapping the trap at its lowest level, substantially as and for the purposes set forth.

4. In an air-storage motor-car or locomotive, the combination with the car-driving engines, of a brake-motor, a reduction-valve, and a hot-water air-reheater through which

the air is usually passed before entering the 25 said engine-cylinder, supplemental or starting connections for said driving-engine, combination-valves controlling the brake-motor connections and said starting connections, a pair of check-valves in the working-pressure pipe between said reduction-valve and said reheater, dry-air-supply pipes for said combination-valves, tapping said working-pressure pipe between said two check-valves, and a drip-pocket or water-trap between said 30 dry-air-supply pipe and the water-check member of said pair of check-valves, with the dry-air connection to the trap at its highest level and the water or wet-air connection to the trap at its lowest level, all for coöperation, substantially as described.

In testimony whereof I affix my signature in presence of two witnesses.

ROBERT HARDIE.
